(74) Attorney, Agent, or Firm — Michael G. Kelber; Neal, Gerber & Eisenberg LLP

(57) **CLAIM**

The ornamental design for audio speaker system, as shown and described.

DESCRIPTION

FIG. 1 is a top perspective view of the audio speaker system in accordance with the present invention;

FIG. 2 is a front view of the embodiment of the audio speaker system depicted in FIG. 1;

FIG. 3 is a rear view of the embodiment of the audio speaker system depicted in FIG. 1;

FIG. 4 is a left side view of the embodiment of the audio speaker system depicted in FIG. 1;

FIG. 5 is a right side view of the embodiment of the audio speaker system depicted in FIG. 1;

FIG. 6 is a top view of the embodiment of the audio speaker system depicted in FIG. 1;

FIG. 7 is a bottom view of the embodiment of the audio speaker system depicted in FIG. 1;

FIG. 8 is a top perspective view of a second embodiment of an audio speaker system in accordance with the present invention;

FIG. 9 is a front view of the embodiment of the audio speaker system depicted in FIG. 8;

FIG. 10 is a rear view of the embodiment of the audio speaker system depicted in FIG. 8;

FIG. 11 is a left side view of the embodiment of the audio speaker system depicted in FIG. 8;

FIG. 12 is a right side view of the embodiment of the audio speaker system depicted in FIG. 8;

FIG. 13 is a top view of the embodiment of the audio speaker system depicted in FIG. 8;

FIG. 14 is a bottom view of the embodiment of the audio speaker system depicted in FIG. 8;

FIG. 15 is a top perspective view of a third embodiment of an audio speaker system in accordance with the present invention;

FIG. 16 is a front view of the embodiment of the audio speaker system depicted in FIG. 15;

FIG. 17 is a rear view of the embodiment of the audio speaker system depicted in FIG. 8;

FIG. 18 is a left side view of the embodiment of the audio speaker system depicted in FIG. 15;

FIG. 19 is a right side view of the embodiment of the audio speaker system depicted in FIG. 15;

FIG. 20 is a top view of the embodiment of the audio speaker system depicted in FIG. 15; and,

FIG. 21 is a bottom view of the embodiment of the audio speaker system depicted in FIG. 15.

The broken lines showing the environment in the Figures are for illustrative purposes only and form no part of the claimed design.
